(57) **CLAIM**

The ornamental design for a tape measure accessory, as shown and described.

DESCRIPTION

FIG. 1 is a front perspective view of the tape measure accessory, showing my new design;

FIG. 2 is a rear perspective view thereof;

FIG. 3 is a front elevation view thereof;

FIG. 4 is a rear elevation view thereof;

FIG. 5 is a left elevation view thereof, the right elevation view being a mirror image thereof;

FIG. 6 is a top plan view thereof; and,

FIG. 7 is a bottom plan view thereof.

The broken lines consisting of evenly spaced lines in the drawings depict portions of the tape measure accessory that form no part of the claimed design, while the broken lines consisting of dash-dot-dash lines in the drawings depict the boundary of the claimed invention and it is understood that the claim extends to the boundary that forms no part of the claimed design.
